UNITED STATES PATENT OFFICE.

CHARLES L. FLACCUS, OF PITTSBURG, PENNSYLVANIA.

DESIGN FOR A BOTTLE.

SPECIFICATION forming part of Design No. 19,669, dated February 25, 1890.

Application filed January 24, 1890. Serial No. 338,014. Term of patent 3½ years.

To all whom it may concern:

Be it known that I, CHARLES L. FLACCUS, a citizen of the United States, residing at Pittsburg, in the county of Allegheny and State of Pennsylvania, have invented and produced a new and original Design for Glass Bottles, of which the following is a specification, reference being had to the accompanying drawing, forming part thereof.

10 The figure is a view in side elevation of my newly-designed bottle.

My design consists in the formation of a bottle in the shape of a child's stocking, such as is represented in a general way in the drawing.

15 Referring thereto, *a* is the stocking, and *b* is the band around the top of the stocking, which is raised or ridged or put on *in in-*

taglio. This band *b* extends entirely around the top of the stocking. The stocking is 20 closed at the top, forming a neck with a cap *c*.

The entire effect of the design when viewed as a whole is the appearance of a child's or baby's stocking as it appears when on the child's foot and filled out by the ankle and 25 limb.

Having thus described my design, I claim herein and desire to secure by Letters Patent of the United States—

The design for glass bottles, as herein 30 shown and described.

CHARLES L. FLACCUS.

Witnesses:

HARRY J. BOOTH,
J. A. NUVERZAGT.
